(57) **CLAIM**

The ornamental design for a clip for gutter guard assembly as shown and described.

DESCRIPTION

FIG. 1 is a perspective view of a first embodiment of a clip for gutter guard assembly;

FIG. 2 is another perspective view of the clip of FIG. 1;

FIG. 3 is a top plan view of the clip of FIG. 1;

FIG. 4 is a bottom plan view of the clip of FIG. 1;

FIG. 5 is a front elevation view of the clip of FIG. 1;

FIG. 6 is a rear elevation view of the clip of FIG. 1;

FIG. 7 is a right-side elevation view of the clip of FIG. 1;

FIG. 8 is a left-side elevation view of the clip of FIG. 1;

FIG. 9 is perspective view of a second embodiment of a clip for gutter guard;

FIG. 10 is another perspective view of the clip of FIG. 9;

FIG. 11 is a top plan view of the clip of FIG. 9;

FIG. 12 is a bottom plan view of the clip of FIG. 9;

FIG. 13 is a front elevation view of the clip of FIG. 9;

FIG. 14 is a rear elevation view of the clip of FIG. 9;

FIG. 15 is a right-side elevation view of the clip of FIG. 9; and,

FIG. 16 is a left-side elevation view of the clip of FIG. 9. The broken lines in the drawings depict portions of the clip for gutter guard assembly that form no part of the claimed design.

1 Claim, 16 Drawing Sheets
